AUDITORIUM CHAIR

Nairne W. Fisher, Chicago, Ill.

Application December 19, 1952, Serial No. 22,783

Term of patent 3½ years

(Cl. D15—8)

To all whom it may concern:

Be it known that I, Nairne W. Fisher, a citizen of the United States, residing at Chicago, in the county of Cook and State of Illinois, have invented a new, original, and ornamental Design for an Auditorium Chair, of which the following is a specification, reference being had to the accompanying drawings, forming a part thereof.

In the drawings—

Figure 1 is a view in perspective of an auditorium chair embodying my new design;

Figure 2 is a top plan view of the auditorium chair shown in Figure 1 of the drawings;

Figure 3 is a view in side elevation of the auditorium chair shown in Figure 1 of the drawings; and

Figure 4 is a view in front elevation of the auditorium chair shown in Figure 1 of the drawings.

I claim:

The ornamental design for an auditorium chair, substantially as shown.

NAIRNE W. FISHER.
